CLAIM

The ornamental design for a battery cable end protector, as shown and described.

DESCRIPTION

FIG. 1 is an end elevational view of a protective case for storage battery terminal post and battery cable end connected thereto showing my new design;

FIG. 2 is a side elevational view thereof, the opposite side being a mirror image;

FIG. 3 is an opposite end elevational view thereof;

FIG. 4 is a bottom plan view thereof; and

FIG. 5 is a top plan view thereof.

FIG. 1

FIG. 2

FIG. 3

FIG. 4

FIG. 5
